POWER DRIVEN HACK SAW

John Henry Guiltman, Spokane, Wash.

Application October 18, 1939, Serial No. 300,056

4 Claims. (Cl. 29—73)

This invention relates to a power driven hack saw, the general object of the invention being to provide a base member, a saw carrying frame vertically movable on the base member and having a horizontal part for extending over the object to be sawed, a saw carrying member supported for horizontal movement by said horizontal part and means for reciprocating the saw carrying member and for moving the horizontal part of the frame vertically so that the saw blade can be moved downwardly against the object to be sawed at the same time the saw carrying member is being reciprocated.

Another object of the invention is to provide means for slightly lifting the saw carrying member on one stroke thereof so as to have the saw cut only on one stroke.

This invention also consists in certain other features of construction and in the combination and arrangement of the several parts to be hereinafter fully described, illustrated in the accompanying drawings and specifically pointed out in the appended claims.

In describing the invention in detail, reference will be had to the accompanying drawings wherein like characters denote like or corresponding parts throughout the several views, and in which:

Figure 1 is an elevation with parts in section of the invention.

Figure 2 is a section on the line 2—2 of Figure 1.

Figure 3 is a section on the line 3—3 of Figure 1.

Figure 4 is a section on the line 4—4 of Figure 1.

Figure 5 is a section on the line 5—5 of Figure 1.

Figure 6 is a section on the line 6—6 of Figure 4.

In these drawings the numeral 1 indicates a tubular upright rising from a base 2 and the numeral 3 indicates a stationary screw shaft having its lower end fastened in the central part of the base 2 and located in the central portion of the tubular member 1. The letter A indicates a frame which includes an elongated horizontal part 6 and a tubular vertical part 7 extending downwardly from one end of the part 6 and this part 7 has a sliding fit in the tubular member 1. Adjacent the lower end of the part 7 is a partition 8 which has a hole therein through which passes a tubular member 9 internally threaded to engage the threads of the member 3. An upper

partition 10 is arranged in the upper portion of the part 7 and the central portion of this partition 10 has a hole therein for the passage of a shaft 11 which carries at its upper end a beveled gear 12, the teeth of which are arranged as shown more specifically in Figure 4 for engagement with a beveled gear 13 on a horizontal shaft 14 journaled in a side of the upper part of the member 7 and which shaft 14 is connected to an electric motor M contained in a casing 15 attached to a side portion of the frame A at the junction of the part 6 with the part 7. This shaft 14 with the armature of the motor can be turned by hand when and if desired as the motor shaft is extended as shown at 16 in Figure 2 through an extension 17 of the casing 15 and the crank handle 18 is adapted to be placed in a socket in the extension 17 and into engagement with the shaft 16 so that by turning the crank 18 the armature of the motor and the shaft 14 can be turned to turn the gear 13 by hand.

The saw carrier is shown at 19 and is of the general shape of a hack saw frame and the blade is shown at 20 and is connected to the carrier 19 in the usual or any desired manner. At one end the carrier 19 is formed with a long shank 21 which passes through openings in an intermediate part of the portion 7 of frame A under the partition 10 so that the carrier 19 is guided as it reciprocates and the top part of the carrier slides along the under part of the portion 6 of the frame A and an upright part 23 extends from the top portion of the carrier 19 into a recess 24 in the bottom part of the portion 6 and a shank 25 extends horizontally from this part 23 and through a groove 26 in the part 6 and into the space formed at the right of the part 6 where it connects with a pitman 27 attached to a crank pin 28 on the gear 13. Thus as the gear 13 is rotated the saw carrier 19 is reciprocated as will be seen.

It will also be seen that as the gear 13 is rotated it will rotate the gear 12 which, in turn, rotates the shaft 11 and said shaft 11 passes into a socket formed in the upper end of the screw shaft 9 where the lower end of the shaft 11 is formed with an enlargement 29 which is held in the socket by a nut 30 threaded in the top part of the socket.

A plate 31 is supported in the upper portion of the part 7 for limited vertical movement and is held against turning movement by the key means shown generally at 32 and the shaft 11 passes through a centrally arranged hole in the plate 31. A pinion 33 is keyed to the shaft 11 for slid-

ing but non-rotatable movement and said pinion meshes with a gear 34 on the upper end of a stub shaft 35 journaled in the plate 31 and having a gear 36 on its lower end meshing with a gear 5 37 fastened to the upper end of the tubular shaft 9 so that turning movement of the shaft 11 is communicated by said gearing to the tubular shaft 9 and the rotary movement of this shaft 9 causes the same to move downwardly or upwardly on the 10 stationary screw shaft 3 and as the parts associated with this shaft 9 are connected with the frame A said frame A is caused to move in a vertical plane with the shaft 9 and this movement of the frame A causes the blade 20 to move toward 15 a piece to be sawed, placed under the saw or to be moved away from said piece.

A spring 40 surrounds the shaft 11 and bears against the pinion 33 and the lower face of the partition 10 and a cam 41 is formed on the bottom of the gear 12 and a cam groove 42 is formed in the upper face of the partition 10 and extends over approximately half of said circular partition 10 as shown in Figure 6, the groove having beveled end walls 43 so the cam 41 can move off the same as it leaves the groove or down a beveled end wall as it enters the groove. This arrangement will cause the spring 40 bearing against the partition 10 to raise the entire frame A when the cam 41 comes opposite the groove so that the cam will enter the groove and this movement is sufficient to raise the blade 20 out of cutting position on the object being sawed and as the groove 42 is of approximately half the circle formed by the member 10 the 30 saw will make one stroke while in raised position and then just before it starts its next stroke the cam will ride out the groove and thus the entire frame with the saw will be pressed downwardly so that the teeth of the saw will engage 35 the object and thus make a cut.

The major portion of the part 6 is of solid construction excepting the recess 24 and groove 26 and these parts are covered by a cover plate 45 and at the free end of the part 6 is a handle 40 grip member 46.

A handle member is also attached to the tubular member 1 but this handle member is not shown as it is located below the casing 15 in Figure 2. This handle member enables the parts to be manipulated without touching the movable part 7. A box-like guiding part 48 is provided on the part 6 at the underside thereof for the front end of the saw frame, as shown in Figure 1 and the cover plate 45 covers this guiding portion and a small casing 49 extends from the part 7 for enclosing the projecting part of the shank 21 of the saw.

Thus it will be seen that the saw is driven from the motor, though it can be driven by hand, 60 and this motion is imparted to the saw in a reciprocatory motion and at the same time the hollow shaft 9 is rotated so that it will move down on the stationary shaft 3, carrying the entire frame A with it so that the saw as it 65 reciprocates and cuts through an object is moved downwardly against the object. However, after each cutting stroke the cam 41 acts with the other parts to slightly raise the saw so that it will make its return stroke without cutting.

70 It is thought from the foregoing description that the advantages and novel features of the invention will be readily apparent.

It is to be understood that changes may be made in the construction and in the combination 75 and arrangement of the several parts provided

that such changes fall within the scope of the appended claims.

Having described the invention, what is claimed as new is:

1. A hack saw comprising a base, a frame supported for vertical movement on the base and including a horizontal part, a saw carrier supported for horizontal movement under the horizontal part, a blade carried by the carrier, means for reciprocating the carrier and at the same time moving the frame downwardly to bring the blade against the piece to be cut, and means for automatically raising the blade out of cutting position on one stroke of the carrier and returning it to cutting position for the next stroke, the latter means including a horizontal part in the frame having a substantially semi-circular groove therein, a rotary member forming part of the means for moving the frame downwardly and a cam on said rotary part for engaging the groove for a part of the revolution of the rotary member and then engaging the horizontal member for the rest of the revolution and spring means for moving the horizontal part, and therefore the frame, upwardly, to cause the cam to engage the groove.

2. A hack saw device of the class described comprising a tubular base, a vertically arranged screw shaft supported against movement in the tubular base, a substantially L-shaped frame having a vertical part slidably fitting in the tubular base, a tubular internally screw-threaded shaft carried by said vertical part and engaging the stationary screw shaft, a blade carrier supported for sliding movement in a horizontal plane on the other part of the L-shaped frame, a motor, a gear rotated by the motor and located at the junction of the two parts of the L-shaped frame, a pitman for connecting the gear with the blade carrier and means connecting the gear with the tubular shaft for rotating the same.

3. A hack saw device of the class described comprising a tubular base, a vertically arranged screw shaft supported against movement in the tubular base, a substantially L-shaped frame 45 having a vertical part slidably fitting in the tubular base, a tubular internally screw-threaded shaft carried by said vertical part and engaging the stationary screw shaft, a blade carrier supported for sliding movement in a horizontal plane 50 on the other part of the L-shaped frame, a motor, a gear rotated by the motor and located at the junction of the two parts of the L-shaped frame, a pitman for connecting the gear with the blade carrier and means connecting the gear 55 with the tubular shaft for rotating the same, said means including a stub shaft, a gear meshing with the first gear and connecting with the stub shaft, and gearing connecting the stub shaft with the tubular shaft.

4. A hack saw of the class described comprising a tubular base, an L-shaped frame including a horizontal part and a vertical part, the vertical part having sliding movement in the tubular base, a motor supported from the L-shaped frame 65 at the junction of the two parts thereof, the vertical part and a portion of the horizontal part of the L-shaped frame being hollow, the motor shaft extending into the hollow part, a gear connected with the inner end of the motor shaft, a reciprocating saw blade carrier supported for sliding movement in a horizontal plane under the horizontal part, a pitman connected with the gear and with the carrier, a stub shaft supported for rotary movement in the 75

vertical part, a beveled gear at the upper end of said shaft meshing with the first mentioned gear, a stationary screw shaft in the tubular base, a tubular internally screw-threaded shaft 5 in the vertical part fitting over the stationary shaft, gearing connecting the stub shaft with the tubular shaft for rotating the same and means for raising the frame slightly after the

blade has made a cutting stroke and holding the parts in raised position as the blade is taking its return stroke and then lowering the frame for enabling the blade to make a cutting stroke, such means including a cam on the second beveled gear and a semi-circular groove in a part of the vertical portion of the frame. 5

JOHN HENRY GUILTMAN.
